FLOAT CONTROL SWITCH

John L. Shrode, Richmond Heights, Mo., assignor
to Alco Valve Company, Inc., St. Louis, Mo.

Application July 12, 1937, Serial No. 153,253

5 Claims. (Cl. 200—84)

This invention relates to electrical circuit make and break mechanism in general; and more particularly to mechanism of this character operable in response to variations in level of a liquid in any 5 vessel to control the supply of liquid thereto.

The main object of the invention is to provide a float controlled switch of the explosion-proof type adapted for use in hazardous atmospheres, such as are encountered in oil level control during 10 the refining processes, whereby the level of highly volatile products, such as alcohol, ether, and refrigerant liquids, may be controlled without danger of ignition caused by sparks which would ordinarily result by the operation of switches 15 having electrical conducting surfaces exposed to the explosive atmosphere.

Other objects of the invention will become apparent as the detailed description thereof proceeds.

20 In the drawings:

Figure 1 is a central vertical section through one form of the invention;

Figure 2 is a horizontal section taken on the line 2—2 of Figure 1;

25 Figure 3 is a central vertical section to a modified form of the invention; and

Figure 4 is a horizontal section taken on the line 4—4 of Figure 3.

Referring now to Figures 1 and 2 of the drawings, the invention comprises a cylindrical body 5 closed at its lower end by a bottom plate 6, having an internally screwthreaded liquid connection 7 formed thereon. A body plate 8 suitably secured to the body 5 near the upper end thereof, forms 35 with said body 5 and bottom plate 6, a pressure chamber 9, the body plate and bottom plate being suitably secured to the cylindrical body 5 as by welding or otherwise. A gas connection 10 is provided in the body 5 near the upper end of the 40 chamber 9, the said gas connection 10 and liquid connection 7 serving to connect the pressure chamber 9 in parallel with any vessel designed to have its liquid level controlled in accordance with the level of liquid in the said pressure 45 chamber.

The body plate 8 is provided at its center with an aperture 11 in which is suitably secured the lower end of a non-magnetic tube 12, the upper end of which serves as a support for the top 13 50 of the relay housing 14. The relay housing 14 is cylindrical and of substantially the same diameter as that of the cylindrical body 5. The lower end of the housing is laterally offset to form an annular flange 15 adapted to fit snugly over the 55 upper end of the body 5.

The shoulder formed in the lower edge of the housing 14 by the annular flange 15 is provided with an annular recess 16 in which is seated the relay housing gasket 17 of rubber, or other suitable resilient material. The upper end of the tube 5 12 is closed by a plug 18 having an externally screwthreaded shank 19 projecting axially through an aperture 20 formed in the center of the top 13 of the relay housing. A nut 21 engages the shank 19 to clamp the housing 14 securely against the gasket 17, and thereby form an effective airtight casing for the electric circuit-closing mechanism above referred to.

The relay or switch mechanism is mounted on and surrounds the non-magnetic tube 12. This 15 mechanism comprises a permanent magnet 22 having the arms 23 and 24 thereof apertured to fit snugly over the tube 12. The magnet 22 is supported in vertical position on the tube 12 by means of a fiber tube 25, the bottom of which 20 rests upon the body plate 8, and the upper end of which contacts with and supports the lower arm 24 of the magnet 22. A short section 26 of fiber tube extends between the upper arm 23 of the magnet and the lower surface of the top 13 25 of the housing 14, to clamp the magnet 22 securely in position on the non-magnetic tube 12.

A float 27 is arranged within the pressure chamber 9, and has a rod 28 extending from its upper end axially into the tube 12. A plunger 29 30 of magnetic material is secured to the upper end of the rod 28. The non-magnetic tube 12 completely encloses the plunger 29 and the rod connecting it to the float 27, and is of sufficient length to permit the necessary axial movement of the 35 plunger in response to liquid level change as imposed upon the float 27 by change in level of the liquid in the pressure chamber 9.

An armature 30 for the magnet 22 is pivoted at its lower end to the arm 24 of the magnet. 40 A pair of tension springs 31 and 32 are secured at one of their ends to the magnet arm 24 and at their other ends are secured to a lug 33 projecting from the lower end of the said armature. Normally these tension springs would hold the 45 armature in the dotted line position shown in Figure 1, with its upper end separated from the upper arm 23 of the magnet. However, the tension of these springs is predetermined so that the attraction of the magnet for the armature will 50 hold it in the full line position shown in the drawings to provide a closed magnetic circuit for the lines of force of the magnet.

When the float supported plunger 29 is raised to a position within the tube 12 in which it com-

plete the magnetic circuit between the pole faces or arms 23 and 24 of the magnet, the magnetic circuit through the armature 30 is weakened, and permits the springs 31 and 32 to pull the armature into the dotted line position shown in the drawings. The swing of the armature about its lower pivoted end may be used to operate any suitable switch or switches into circuit-making or circuit-breaking position, in accordance with the requirements of the apparatus designed to be controlled thereby. As shown in the drawings, the switch comprises a leaf spring 34 suitably secured to the lower part of the armature 30 and having a contact terminal 35 fixed to its outer end adapted to make contact with a cooperating terminal 36 fixed to a bracket 37 insulated from and suitably secured to the relay housing 14. Suitable wires 37 and 38 connect the respective terminals 35 and 36 to any apparatus designed to be controlled thereby. A conduit connection 39 is secured to the upper end of the body 5 above the body plate 8 to serve as a passageway for such wiring as may be necessary to connect the relay to the said apparatus.

The modified form of the invention illustrated in Figures 3 and 4 is substantially the same as that shown in Figures 1 and 2. In this form, however, an electrical induction coil 40 and a magnetic frame 41 are substituted for the permanent magnet 22, shown in Figure 1, the coil 40 being retained in place between the arm or pole pieces 42 and 43 by means of a screw 44 passing freely through an aperture in the pole piece 42 and screwthreaded into an internally screw-threaded aperture in the lower pole piece 43. The armature and other operating parts connected thereto are substantially the same as the corresponding parts shown in Figure 1 and are identified by the same reference numerals.

When low temperatures are encountered, such as commonly occur in refrigerated vessels, it is desirable to isolate the relay mechanism so as to permit insulation of the pressure chamber 9, in order that violent ebullition created by high rates of heat absorption will not cause false liquid levels within the float chamber. It is also desirable to effect this isolation and insulation in order to prevent freezing of the mercury within the mercury switches, when switches of this character are used within the relay housing.

The insulation above referred to comprises a block of cork 45, centrally apertured to receive the non-magnetic tube 46 secured at its lower end to the body plate 8'. The tube 46 is substantially the same as the tube 12, shown in Figure 1 of the drawings, and is similarly secured at its upper end to the relay housing 14, which in every respect is the same as that shown in Figure 1. The tube 46 must, of course, be correspondingly lengthened to compensate for the length of the insulation insert 45. The lower end of the relay enclosing chamber is formed by a cylindrical container 47, the bottom of which is centrally apertured to receive the tube 46, and is provided with an upstanding annular boss or flange 48 serving as a seat for the lower end of the tube 25', which forms a support for the magnetic frame 41. The other elements of this form of the invention are the same as are shown in Figure 1 of the drawings and are identified by the same reference numerals.

While the switches shown in the drawings are of the common spring contact type, it must be understood that the invention is not to be considered as limited to any particular kind of switch.

It is contemplated that the well-known mercury switches may be used in place of those illustrated; and that any other type of switch capable of being operated by rotation of the armature 30 about its pivot point may be employed in place of those illustrated.

What I claim is:

1. A switch comprising a horse shoe magnet, a non-magnetic tube extending through the pole pieces thereof, an armature pivoted to the end 10 of one of said pole pieces to swing toward and from the other pole piece and normally held by said magnet in position to close the magnetic circuit therethrough, means for swinging said armature away from said other pole piece when the 15 flux through the magnet is shunted from said armature, a plunger of magnetic material slideable in said tube to bridge said pole pieces, and a circuit maker and breaker connected to said armature for operation by the movements thereof. 20

2. Liquid level-controlled electric switch mechanism, comprising a casing, a partition dividing the casing into a liquid-containing chamber and a relay housing, a horse shoe magnet mounted in said housing, a non-magnetic tube extending 25 from said chamber through said partition and the pole pieces of said magnet, an armature pivoted to one of said pole pieces to swing toward and from the other pole piece and normally held by said magnet in position to close the magnetic circuit therethrough, means for swinging the armature from said circuit-closing position when the flux through the magnet is shunted from said armature, a float within said chamber, a plunger connected to said float and slideable in said tube 30 transversely of said pole pieces to shunt said armature, and a circuit maker and breaker connected to said armature for operation by the swinging movements thereof.

3. Liquid level-controlled electric switch mechanism, comprising a casing, a partition dividing the casing into a liquid-containing chamber and a relay housing, a horse shoe magnet mounted in said housing, a non-magnetic tube extending 35 from said chamber through said partition and the pole pieces of said magnet, an armature pivoted to one of said pole pieces to swing toward and from the other pole piece and normally held by said magnet in position to close the magnetic circuit therethrough, means for swinging the armature from said circuit-closing position when the flux through the magnet is shunted from said armature, a float within said chamber, a plunger connected to said float and slideable in said tube 40 transversely of said pole pieces to shunt said armature, and a circuit maker and breaker connected to said armature for operation by the swinging movements thereof, said partition and tube forming 45 an hermetic seal between said chamber and the circuit-closing mechanism in the relay housing. 50

4. Liquid level-controlled switch mechanism comprising: a casing, a partition dividing the casing into a liquid container and a relay housing, a tube of non-magnetic material extending 55 from said chamber and through said partition into said housing and hermetically sealing the housing from said container, a horse shoe magnet mounted in said housing and having the pole pieces thereof provided with apertures through 60 which said tube extends, a float in said container, a plunger of magnetic material mounted on said float to slide in said tube transversely of said pole pieces, and circuit make and break mechanism pivoted to one of said pole pieces and oper- 75

ably controlled by the movements of said plunger in said tube.

5. A switch comprising a horse shoe magnet, an armature pivoted at one end to one of the pole pieces of said magnet to swing toward and from the other pole piece and normally held by said

magnet in position to close the magnetic circuit across said pole pieces, means for swinging the armature away from said other pole piece, and circuit make and break mechanism operably controlled by the swinging of said armature.

JOHN L. SHRODE.
